UNITED STATES PATENT OFFICE

GARFIELD W. FISHER AND CARL G. HENRIKSON, OF ANDERSON, INDIANA, ASSIGNORS
TO THE NATIONAL TILE COMPANY, OF ANDERSON, INDIANA, A CORPORATION
OF OHIO

MOLD FOR TILES

Application filed April 23, 1928. Serial No. 272,202.

Our invention relates to molds for tiles and it is an object of the invention to provide a mold or die which will in one operation press or form the tile into shape and bevel 5 the edges of the same, all as will be herein-after more particularly described and claimed.

Referring to the accompanying drawings which are made a part hereof and on which 10 similar reference characters indicate similar parts,

Figure 1 is a top plan view of the bottom member of the mold or die,

Figure 2, a central transverse section of 15 the cooperating upper and lower members of the mold or die disposed in opposed spaced relation,

Figure 3, a similar view with the parts in 20 the position at the end of the pressing operation,

Figure 4, a bottom plan view of the upper movable member of the mold,

Figure 5, a section on the line 5—5 of Figure 4, and

25 Figure 6, a section on the line 6—6 of Figure 1.

In the drawings reference character 10 indicates a support upon which is mounted an outer stationary frame or die box 11 held in 30 position by bolts 12.

Within the outer die box 11 is mounted an inner frame or die box 15 which is normally supported with its upper surface flush with the upper surface of the outer die box 11. 35 The inner die box is of substantially hollow rectangular form and extends at opposite sides over the spring retainer members 13, which are fixed to the under side of the outer die box by means of screws 14. The retainer members 13 are provided with vertical recesses or pockets 16 in each of which is disposed a helical spring 17 having an inverted cup or cap 18, Figure 6, which telescopes 40 over the spring into the recess or pocket 16 and engages the under side of the inner die box 15 holding it in the above mentioned elevated position. In order to limit the upward movement of the inner die box under the tension of the spring 17, an elongated member 45 50 19 is fastened at each end by means of screws

20 on the under side of the inner die box and such elongated member has a lateral extension 21 at each end which projects beneath the outer die box and forms a stop.

The inner die box 15 incloses a die or lower 55 plunger 22 which has its upper surface formed for giving the proper impression to the material 23, such die being attached to a supporting block 24 upon which it is mounted by means of screws 25. The supporting 60 block 24 is secured upon a backing plate 26 by means of screws 27, said backing plate being mounted upon the lower movable member of the press (not shown).

An upper reciprocable die or plunger is 65 provided which in the present instance comprises an edging strip 28 arranged in the form of a hollow rectangle over the inner die box 15. The edging strip 28 is provided with a longitudinal groove 28' which forms an exit 70 for air compressed by the action of the press. A die plate 29 is supported inwardly of the edging strip and both the edging strip and die plate are secured to a backing plate 30 carried by the upper ram or plunger 31 of 75 the press.

In operation at the beginning of the press stroke as shown in Figure 2, the lower punch or plunger 22 is within the inner frame or die box 15, with the top of said inner box 80 flush with the top of the stationary die box 11, and it is held there by the action of the helical compression spring 17 acting against the bottom of the inner box, the lateral extensions or stops 21 resting against the under 85 side of the outer stationary die box 11. Material to be operated upon is supplied upon the lower die member or plunger 22 and as the upper die member or plunger descends (see Figure 3) it enters the outer stationary 90 die box with the edging strip fitting snugly within the same, and the inner box or die member 15 is forced down against the compression of the springs 17. The tile is thus 95 formed between the upper and lower die members, the inner walls of the inner box and the beveled edges of the edging strips. Any air escaping from the upper part of the form is forced along the narrow space between the inner box and edging strips into the chan- 100

nels 28 in said strips. The upper die member of the press now ascends, the compression springs forcing the inner box to its original position as at the beginning of its stroke, and the lower punch ascends, ejecting tile from the inner box, and again descends to original position, which completes the operation.

It will be obvious to those skilled in the art that various changes may be made in our device without departing from the spirit of the invention, and we, therefore, do not limit ourselves to what is shown in the drawings and described in the specification, but only as set forth in the appended claims.

Having thus fully described our said invention what we claim as new and desire to secure by Letters Patent, is:

1. A mold or die for tile, comprising means for pressing the tile into shape and for simultaneously shaping the edge of the tile, said means comprising an inner box and an outer box, upper and lower die members, a mitered frame around the upper die member movable within the outer box, and springs holding the inner box against said frame, substantially as set forth.

2. The combination in a mold or die for forming tile, of a stationary box, a movable frame within said box, a die member reciprocably mounted within said frame, a co-operative opposed die member movable into said box and adapted to move the frame relative to the box, substantially as set forth.

3. The combination in a mold or die for forming tile, of a stationary box, a movable frame within said box, a die member reciprocably mounted within said frame, a co-operative opposed die member movable into said box and adapted to move the frame relative to the box, said co-operative opposed die member being provided with an edging strip around its periphery for shaping the edge of the tile, substantially as set forth.

4. The combination in a mold or die for forming tile, of a stationary box, a movable frame within said box, a die member reciprocably mounted within said frame, a co-operative opposed die member movable into said box and adapted to move the frame relative to the box, said co-operative opposed die member being provided with an edging strip around its periphery for shaping the edge of the tile, said edging strip having a longitudinal groove for permitting the escape of air, substantially as set forth.

5. A machine for forming tiles comprising opposed movable die members, a casing about one of the movable members adapted to define the length and breadth of the tile, a co-operating movable member having a rim which projects over the casing, and yielding supporting means for said casing, substantially as set forth.

6. A machine for forming tiles comprising

ing opposed movable die members, a casing about one of the movable members adapted to define the length and breadth of the tile, a co-operating movable member having a rim which projects over the casing, and yielding 70 supporting means for said casing, said rim being provided with a longitudinal depression for permitting the escape of entrapped gas, substantially as set forth.

In witness whereof, we have hereunto set 75 our hands and seals at Anderson, Madison County, Indiana, this 21st day of April, A. D. nineteen hundred and twenty-eight.

GARFIELD W. FISHER.
CARL G. HENRIKSON.
